HENRY HENRICH, OF NEW YORK, N. Y., ASSIGNOR TO J. R. WOOD & SONS, OF NEW YORK, N. Y., A CORPORATION OF NEW YORK.

FINGER-RING-MARKING MACHINE.

No. 895,180.

Specification of Letters Patent.

Patented Aug. 4, 1908.

Application filed February 26, 1907. Serial No. 359,480.

To all whom it may concern:

Be it known that I, HENRY HENRICH, of New York city, in the county of New York, and in the State of New York, have invented 5 a certain new and useful Improvement in Finger-Ring-Marking Machines, and do hereby declare that the following is a full, clear, and exact description thereof, reference being had to the accompanying drawing, in which—

Figures 1 and 2 are respectively a side and end elevation of a machine embodying my invention; Fig. 3 is a view, principally in section, in the plane of the spindle of the machine; and Fig. 4 is an enlarged sectional view of the ring-holding parts, with the tool in elevation, in a plane transverse to the spindle.

The object of my invention has been to 20 provide a machine for marking finger-rings which shall be capable of marking such rings after they are turned or rolled, and without injuring the outer surface, or distorting their shape; and to such ends my invention consists in the finger-ring marking machine hereinafter specified.

In carrying my invention into practice, I provide a frame 10, having bearings for a hollow spindle 11. A gear 12 is keyed on the 30 rear end of said spindle, and is secured in place by a nut 13. The gear and spindle are adapted to be driven by a pinion 14, on whose sleeve is secured a crank 15, the pinion and sleeve being mounted on a stud 16 that 35 is secured to the frame.

Other forms of driving mechanism for a spindle can, of course, be employed. The gear prevents forward movement of the spindle, and a collar 17 secured upon the 40 spindle close to one of the bearings prevents movement of the spindle in the opposite direction. The shank of the tool 18 is mounted in the forward end of the spindle, and is prevented from rotation relative to the spindle by a set-screw 19. The tool projects beyond the forward end of the spindle, and has formed thereon a die 20, by which the impression is to be made on the inside of the ring. The die is raised above the surface of 50 the shank of the tool, and the shank is of such diameter that the die does not extend around its entire circumference, for a purpose to be later explained.

In order to support the ring, and to prop-

erly present it to the die, the following means 55 are provided: A pair of guides 21 is formed on the frame, and the vertical arm of a bracket 22 is mounted on such guides. Means are provided for raising and lowering the bracket on the guides 21, the means which I 60 have chosen as most convenient being a screw 23 that is threaded into the bracket parallel to the guides, and that has its lower end journaled in a socket in the frame. The screw is provided with a hand-wheel 24 for 65 turning it. Obviously, the screw could be screwed into the bracket and threaded into the frame, and the same results would be produced. The bracket has a horizontal arm 26 in which are formed a pair of guides 27 parallel to the spindle. A slide 28 is mounted in the guides 27, and is provided with a box 29, whose bottom is formed on the arc of a circle. Within the box are mounted a series of rollers 30. These rollers may, if desired, be mounted upon pistons, but I prefer to leave them loose in the box, so that they may roll upon its bottom. A ring-holder 31 rests upon the rollers, the line formed by the upper surfaces of such rollers being the arc of a circle of the 70 same curvature as that formed by the inner points of the series of rollers. The ring-holder has an inner surface 32 that is concentric with the outer surface, and that has in it a groove 33 of such cross section as to accurately fit the ring to be marked. The ring-holder preferably forms but part of a circle, but it could be made to form a complete circle. I find it practicable to use but a single 75 ring-holder for a series of rings of different diameters, but of the same cross section. In order to adjust the ring-holding groove directly under the die, I provide a thumb-screw 34, which is threaded into the slide, and is adapted to extend through the slide and 80 strike against the frame. A thumb-nut 35 serves to lock the thumb-screw 34 in adjusted position.

In the operation of the above illustrated embodiment of my invention, the slide is retracted until the ring-holding groove is out from beneath the die, and the ring is then placed in said groove. The spindle is turned so that the die is on its upper side, and the slide is moved toward the frame, carrying the ring beneath the die. Because the die does not extend entirely around the shank of the tool, it is out of the way when it is turned 100 105

into its upper position, and thus the ring can be moved into position beneath the die without any vertical movement of the bracket. This permits the bracket to be adjusted once for a series of rings, and then the series to be marked without vertically moving the bracket between the marking of any two rings. The spindle is then rotated once, and the die, as it passes through the lower portion of its travel, is impressed into the ring with all desired force, and is then disengaged from the ring as it rises again to its upper position. The slide is then retracted, and the marked ring removed from the ring-holder.

15 It will be observed that while the series of rollers effectively supports the ring-holder against great pressure, it permits the ring-holder to move with such ease that there is no danger of dragging the ring in the ring-holding groove. It will also be observed that one ring-holder can be substituted for another with the greatest ease. It should further be noticed that the rings are placed in the ring-holder and carried beneath the die and then removed after being marked, with great facility. The ring-holder effectively supports the ring so that the die does not distort the ring either laterally or longitudinally.

20 While I have described what I consider to be the best embodiment of my invention, I desire it to be understood that the principles can be embodied in different forms, and I desire not to be limited beyond the requirements of the prior art, and the terms of my 25 claims.

Having thus described my invention, I claim,

1. In a ring-marking machine, the combination of a spindle having a die mounted thereon and extending part only of a circle, a ring-holder having a ring-receiving groove, and a slide carrying said ring-holder, said slide being movable parallel to said spindle.

2. In a ring-marking machine, the combination of a spindle having a die mounted thereon and extending part only of a circle, a rotatable ring-holder having a ring-receiving groove, and a slide carrying said ring-holder, said slide being movable parallel to said 45 spindle.

3. In a ring-marking machine, the combination of a spindle having a die mounted thereon and extending part only of a circle, an arc-shaped ring-holder having a ring-holding groove of substantially the same cross section as the ring, and means permitting move-

ment of said ring-holder concentric with said groove.

4. In a ring-marking machine, the combination of a spindle having a die thereon, an arc-shaped ring-holder having a ring-holding groove of substantially the same cross section as the ring, and means permitting the movement of said holder concentric with said groove. 65

5. In a ring-marking machine, the combination of a spindle having a die thereon, a ring-holder having a ring-holding groove, and means for adjusting said holder parallel and transverse to said spindle. 70

6. In a ring-marking machine, the combination of a spindle having a die mounted thereon, a rotatable ring-holder having a ring-holding groove, and means for adjusting said holder parallel and transverse to said spindle. 75

7. In a ring-marking machine, the combination of a spindle having a die mounted thereon and extending part only of a circle, a ring-holder having an arc-shaped ring-holding groove and having an outer surface concentric with said groove, a box having a curved bottom, and a series of rollers mounted in said box and supporting said ring-holder. 80

8. In a ring-marking machine, the combination of a spindle having a die mounted thereon and extending part only of a circle, a ring-holder having an arc-shaped ring-holding groove and having an outer surface concentric with said groove, a box having a curved bottom, a series of rollers mounted in said box and supporting said ring-holder, and a slide on which said box is mounted, said slide being movable parallel to said spindle. 85

9. In a ring-marking machine, the combination of a spindle having a die mounted thereon and extending part only of a circle, a ring-holder having an arc-shaped ring-holding groove and having an outer surface concentric with said groove, a box having a curved bottom, a series of rollers mounted in said box and supporting said ring-holder, a slide on which said box is mounted, a bracket movable on the frame of the machine transverse to said spindle, and a guide-way on said bracket parallel to said spindle, said slide being mounted in said guide-way. 95

In testimony that I claim the foregoing I have hereunto set my hand.

HENRY HENRICH.
